UNITED STATES PATENT OFFICE.

OSCAR GRAHN, OF LONDON, ENGLAND, ASSIGNOR TO THE RELAY AUTOMATIC TELEPHONE COMPANY, LIMITED, OF LONDON, ENGLAND.

AUTOMATIC AND SEMI-AUTOMATIC TELEPHONE SYSTEM.

1,807,196.

Specification of Letters Patent. Patented June 17, 1919.

Application filed March 20, 1917. Serial No. 156,047.

To all whom it may concern:

Be it known that I, OSCAR GRAHN, a subject of the King of Sweden, residing at Marconi House, Strand, London, England, have invented new and useful Improvements 5 in Automatic and Semi-Automatic Telephone Systems, of which the following is a specification.

The invention relates to improvements in 10 automatic and semi-automatic telephone systems and more particularly to multi-office systems including both manual and automatic exchanges. The object of the invention is to provide circuits for carrying out 15 certain operations over the talking connection, such as metering, disconnection and control of supervisory signals, and so to arrange said circuits that they may perform 20 the functions required in different kinds of connections.

For instance, in a connection between two subscribers of an automatic exchange, it may be required that only effective calls shall be registered, that no registration shall be made 25 for calls to certain subscribers and that the connection shall be automatically released in case the called subscriber is engaged. In a connection between a subscriber of an automatic exchange and an operator of a manual 30 exchange, it may be desired that the operator, when answering, shall take charge of the connection and control the release of the junction between the exchanges, and further that a clearing signal shall be given to the operator 35 from the calling subscriber. When the call is from a manual exchange to a subscriber of an automatic exchange, the operator shall be given suitable supervisory signals such as clearing signal from the called 40 subscriber and a flash signal when the called subscriber is engaged.

As seen from these conditions the problem is largely a matter of providing circuits in connection with inter-office junctions and 45 trunks in automatic exchanges capable of transmitting different signals or current combinations over the talking connection to effect certain operations at the calling and the called end of the connection, and so designed 50 that they work together properly in different kinds of connections.

According to the present invention, in order to utilize the two line branches of the talking connection more efficiently for said

purposes, two relays controlling metering, 55 disconnecting and supervisory circuits are associated with each trunk or junction and connected each to one line branch, means being provided at the called end of the connection to operate said relays separately or together. 60 To be able to use said relays for disconnecting purposes, they preferably remain connected to the line branches during the conversation, energized in a loop circuit extending over the line of the called subscriber or 65 over a junction. Further features of the invention will be described in connection with the accompanying drawings in which:—

Figure 1 illustrates part of a talking connection with the principal circuits of a set 70 of transmitting relays according to this invention:

Fig. 2 shows the calling end of a talking connection in an automatic exchange in which the connections are established by 75 means of relays only:

Fig. 3 shows the called end of a talking connection in an automatic exchange:

Fig. 4 shows the transmission circuits associated with the incoming end of a junction 80 line connecting two automatic exchanges:

Fig. 5 shows the principal circuits associated with the incoming end of a junction joining an automatic and a manual exchange or an automatic subscriber with a manual 85 board at the automatic exchange:

Fig. 6 shows the principal circuits at a manual exchange for calls to an automatic exchange and

Fig. 7 shows the transmission circuits as- 90 sociated with the incoming end of a junction connecting a manual and an automatic exchange.

In Fig. 1, A, B, C, D, E, are a set of transmission relays associated with a trunk leading to the first group switching stage in an automatic exchange. A and B are two transmitting relays according to the invention, connected each to one line branch of said trunk and controlling certain circuits 100 1, 2, 3. C, is an impulse relay, and D and E the ordinary guarding and change-over relays, which are slow to release their armatures. The impulse relay C, upon energizing, cuts in the guarding relay D, which 105 then remains in operated position till the connection is completed, as will be described below. During the transmission of the se-

lective impulses, relay E is maintained energized in known manner so that relays A and B are disconnected from the trunk.

The relays A and B are operated from the called end of the connection by means of devices here represented by two keys AK and BK. By operating key BK after the completion of the connection, *i. e.*, after relay D has deenergized, relay B is retained while A deenergizes, closing a circuit 1 which may be a meter circuit, or may be utilized for preparing the meter circuit, if the call is to be registered after the end of the conversation. By operating key AK at the end of the conversation, A is retained while B deenergizes, completing a circuit 2 which may be utilized for clearing purposes. In case the called subscriber should be engaged, key BK is operated before the guarding relay D has deenergized thereby completing a circuit 3 which is utilized for busy-back signal and busy-back release.

A local automatic connection will now be described with reference to Figs. 2 and 3. The calling subscriber S1, when lifting his receiver, completes a circuit 4 through a line relay LR1 which causes apparatus common to a number of subscribers to test the trunks T1 available to said subscribers and to operate those connecting relays CR1 and CR2 by which the calling line L1 can be connected to an idle trunk. The operations that take place are in all respects similar to those described in the British Patent Specification No. 9840/1914, and need not therefore be particularly described in this connection. The impulse relay C is now energized over the subscriber's line and completes a retaining circuit 5 including said connecting relays CR1 and CR2 and a cut-off relay COR1. The latter operates, opens circuit 4 and energizes an auxiliary relay AR1 over 6. Relay C, upon operating, closes a circuit 7 through the guarding relay D and a circuit 8 through a selector connecting relay SCR1 belonging to a first group selector (not shown) which may be common to a number of trunks T1 as described in the British Patent Specification No. 29,615 of 1913. Relay SCR1 completes circuit 9 which includes relays A and B and a selector impulse relay SIR1. Such relays energize B closing a holding circuit 10 for relay D.

The subscriber now sends the impulses corresponding to the first digit of the number required. Upon the first deenergization of C, relay E is energized over 11, whereby the selector impulse relay SIR1 is switched over without interruption in a circuit 12 controlled by C. When C reenergizes, the secondary impulse circuit 12 is opened for the first time. During the sending of the impulses A and B are deenergized while the guarding relay D is kept energized over a

circuit 13. Relay D maintains the third wire circuits 5 and 8 over contact 24. After the selector has been set it automatically puts into operation a device which selects and operates two connecting relays CR3 and CR4 by which trunk T1 is connected to an idle trunk T2 outgoing in the required direction to the next group switching stage or to the final switching stage, the group selector being automatically disconnected by the operation of relay CR3. The operation of the selector, which has nothing to do with the invention, may be similar to that described in said Specification No. 29,615 of 1913.

Supposing said trunk T2 is a trunk leading to the final switching stage, as shown in Fig. 3, a third wire retaining circuit 14 is now completed through relays CR3 and CR4 and a selector connecting relay SCR2. At about the same moment relay E deenergizes closing circuit 15 through relays A and B and the impulse relay SIR2 of the final selector (not shown).

The subscriber now sends the second train of impulses corresponding to the hundreds digit of the number wanted. The change-over relay E energizes on the first deenergization of C, cuts off A and B, which again deenergize, and completes the impulse circuit 16. The final selector is set by two trains of impulses operating chiefly as described in said specification 9840 of 1914. After having been set, it causes the energization of a set of connecting relays CR5, CR6 and CR7 by which the trunk T2 is connected with the line L2 of the wanted subscriber S2. The final selector is therefore disconnected and the retaining circuit 14 is maintained through CR5. The latter completes another retaining circuit 17 through CR6 and CR7 a discriminating relay M² and the cut-off relay COR2 of the called subscriber. A relay H is initially energized in a circuit parallel to that energizing CR5, and is retained over 18. Relay COR2 energizes AR2 which disconnects the line relay LR2. Relay M energizes if the called subscriber is an ordinary subscriber. If the called subscriber is one to whom calls are free, said relay does not operate owing to a resistance being inserted in the third wire circuit of such subscriber, for instance, between relays COR2 and AR2. At first it may be assumed that M does operate so that the call may be registered.

The subscriber is now rung automatically in ordinary way by means not shown here. In the meantime relay D, Fig. 2, deenergizes, as relays A and B now remain deenergized. When the subscriber lifts his receiver to answer, a circuit 19 is closed through one winding of a relay K, Fig. 3, the line of the called subscriber and relay A, Fig. 2. Relay K operates, locks itself

in a retaining circuit 20 and opens said circuit 19. At the same time it opens the circuit of H and closes a circuit 21, relay H being slow-acting so as to maintain circuit 21 for a moment. Relay B, Fig. 2, energizes in said circuit and closes a circuit 22 through a meter relay G which is retained over 23. Relay B also completes a circuit 25 in which a disconnecting control relay F is energized. The third wire circuits 5 and 14 are now maintained over 26 and are thus under the control of relay B.

Relay H, upon deenergizing, closes a loop circuit 27 through relays A and B and the called subscriber's line, whereby the connection is put into condition for conversation.

If the called subscriber is the first to restore his receiver, relays A and B deenergize but nothing further happens, as relay F and the third wire circuits 5 and 14 are maintained over 28, F, being slow to release its armature. When the calling subscriber replaces his receiver, relay C deenergizes and opens circuit of G which, however, being slow-acting, keeps its armature attracted for a short interval during which a resistance R1 in circuit 5 is short-circuited over 30, whereby the calling subscriber's meter (not shown) which is included in the third wire circuit 5, is operated in well-known manner. When G deenergizes, the retaining circuits 5 and 14 hitherto maintained over 30 are opened and the connection is released.

Should the calling subscriber be the first to replace his receiver, relay B is short-circuited over 31 and deenergizes while relay A remains energized over 31. The meter is operated as before and the connection is released when G deenergizes.

If the call is not to be registered, relay M, Fig. 3, is not energized and, consequently, circuit 21 is not closed and the meter relay G remains deenergized. When relay H, Fig. 3, deenergizes, the loop circuit 27 is closed as before. The connection is released without metering, when the calling subscriber replaces his receiver.

In case the called subscriber should be engaged in the moment of establishing the connection, the connecting relays CR6 and CR7 cannot be operated and a circuit 32 is therefore completed through a relay N which operates and energizes K, which locks itself as before. Relays K and N complete circuit 21 through contact 33 of relay N, thereby causing a momentary energization of relay B, Fig. 2. At this moment, however, the slow-acting guarding relay D has not had sufficient time to deenergize and a circuit 34 is therefore completed through relay F which maintains the third-wire circuits 5 and 14 over the same path 34. When relay H deenergizes, B deenergizes, the retaining circuits 5 and 14 are opened and the connection is severed up to the calling subscriber's

line. The calling subscriber's cut-off relay COR1, on deenergizing, completes a retaining circuit 35 through relay AR1 and the line L1. A transformer 36 adapted to give a busy-back signal is then connected up to 70 the line. When the subscriber hears the busy-tone he replaces the receiver, thereby opening circuit 35.

The circuits for a connection between two subscribers belonging to two different automatic exchanges are obtained by placing together Figs. 2, 4 and 3 in the order mentioned. Circuit 14 of relay CR4, Fig. 2, is then connected directly to battery. The connecting operations are the same as before 80 described. When connection is made with the junction line J1, a circuit 37 is closed through an impulse relay C', Fig. 4; and relay A, Fig. 2. Relay C' energizes and closes a circuit 38 through a selector connecting relay SCR3 of a second group - selector and a circuit 39 through the guarding relay D'. Relay SCR3 completes loop - circuit 40 through relays A' and B' and the selector impulse relay SIR3. D' is retained over 85 41. 90 A' and B' close a loop-circuit through relays A and B, Fig. 2, over 42, Fig. 4, and through relay C'. The selector is now operated in the ordinary way, relay D' being retained and E' energized in the manner described in connection with Fig. 2. During the sending of the impulses A' and B' are deenergized but the loop - circuit extending over the junction and through relay C' is maintained over 43. After the second group 100 selector has been set, the connecting relays CR8 and CR9 are operated as before described and the connection is extended to the trunk T2, Fig. 3, and to a final selector which is operated to complete the connection as 105 previously described.

While the called subscriber is being rung, D', Fig. 4, deenergizes. The loop circuit over the junction is therefore opened and circuit 37 is reestablished whereby B, Fig. 2, 110 is allowed to deenergize. When the subscriber answers, assuming that the call is to be registered, a circuit 21 is again established as before described, this time, however, through relay B¹, Fig. 4. This results in the 115 energization of the corresponding relay B, Fig. 2, over 44. At the same time a relay U is energized over 45 and retained in the third wire to prevent disconnection by the called subscriber at the end of the conversation. Relay B, Fig. 2, energizing, operates the meter relay G as before. When H, Fig. 3, deenergizes, the loop-circuit 27 is established through relays A' and B' and the called subscriber's line L2. A' and B' complete the loop circuit 42 through relays A and B, the junction J1 and relay C'. 120 125

When the called subscriber replaces his receiver, A' and B' deenergize, but the loop-circuit of relays A and B is now maintained 130

through C' over a path 46 controlled by relay U and back contacts of A' and B'. When the calling subscriber restores his receiver, relay B, Fig. 2, is short-circuited over 5 31 to prepare the release by opening the path 26. The connection is released when G de-energizes after having secured the operation of the meter in the manner described.

A connection between a subscriber of an 10 automatic exchange and a cord circuit at a manual exchange is illustrated by Figs. 2 and 5. When the calling subscriber is connected to the junction J2, a circuit 47 is established through relay A, Fig. 2, and a 15 supervisory relay V which closes a lamp circuit 48. The operator, seeing the lamp glowing, depresses the speaking key (not shown) ascertains the number wanted and inserts the plug P in the corresponding jack. 20 Relay W operates, shunts the lamp and completes at contact 49 the loop circuit through relays A and B and the junction J2. Relay B, energizing, operates relay F and completes the path 26 over which the connection 25 is now maintained under the control of the operator.

At the end of the conversation, when the calling subscriber replaces his receiver, relay V, Fig. 5, is short-circuited over 31, and on de-energizing removes the shunt across the 30 supervisory lamp. Relay B remains energized over the corresponding line branch thus maintaining the connection. The operator, seeing the lamp glowing, depresses a 35 meter key MK, if the call is to be registered, thereby short-circuiting relay A which, on de-energizing, operates the meter relay G. The meter is immediately operated over 30. To release the connection the operator with- 40 draws the plug, thereby opening contact 49 of relay W and causing relay B to de-energize. Relay B opens the path 26 and thereby the third wire retaining circuits 5 and 14.

Figs. 6, 7 and 3, placed together in the 45 order mentioned, show a connection between a cord circuit at a manual exchange and a subscriber of an automatic exchange. The junction J3 has associated with it an impulse sender key SK, by means of which an 50 impulse sender of any known type can be connected to the line, and at the automatic exchange, Fig. 7, a set of transmission relays A'', B'', C'', D'' and E'' controlling circuits in substantially the same manner as 55 the relay set shown in Fig. 4. To establish a connection the operator inserts plug P2 in the jack of an idle junction J3 and pulls key SK to connect up the impulse sender. A circuit 50 is then closed through one line 60 branch and relay C'', Fig. 7. The latter energizes and operates a selector connecting relay SCR4. A loop circuit is then completed as in Fig. 4, through relays A'', B'' and the selector impulse relay SIR4. A'' 65 and B'' operate and close a loop circuit 51

through C'', the junction J3 and the impulse sender. The impulses are now sent and the connection is built up in the manner described with reference to Figs. 2 and 3. Having sent the last train of impulses, 70 the operator pulls key SK to disconnect the impulse sender. While the wanted subscriber is being rung, relay D'', Fig. 7, de-energizes and completes a circuit 52 through C'' and one line branch of the junction. 75 When the subscriber answers, circuit 21, Fig. 3, is closed through relay B''. The latter operates, closes a circuit 53 through relay C'' and the other line branch of the junction and opens circuit 52. The supervisory relay 80 SR1 energizes in circuit 53 and short-circuits the lamp SL1, whereby the operator is informed that the called subscriber has answered. When relay H, Fig. 3, de-energizes, the loop circuit 27 is closed through relay 85 A'' and B''. The latter close in turn loop-circuit 51 through relay C'' and the cord circuit, the supervisory lamp thus remaining short-circuited. When the called subscriber replaces his receiver, A'' and B'' de-energize, open the loop circuit 51 and close 90 circuit 52. Lamp SL1 glows, indicating that the called subscriber has cleared. Upon withdrawing plug P2 circuit 52 is opened, C'' de-energizes and the connection is released. 95

In case the called subscriber should be engaged, relay B'', Fig. 7, is energized over 21, Fig. 3, before relay D'' has de-energized and a circuit 54 is therefore established in 100 which a busy-flash relay Q is energized. The latter locks itself over 55 and completes a circuit 56, including an interrupter I and extending over one line branch through the supervisory relay SR1. The lamp SL1 is 105 thereby flashed informing the operator that the called subscriber is busy. Meanwhile relay C'' is kept energized over 57 to maintain the connection. When relay H, Fig. 3, de-energizes, relay B'' de-energizes, relay C'' 110 being then maintained energized first over 58 and then, after D' has deenergized, over 52. The connection is released as before by withdrawing the plug P2.

What I claim is:—

1. In a telephone system, two relays each connected to a different line branch of a talking connection, means associated with a called junction for operating either of said relays over the talking connection and means for completing a loop-circuit through said relays over the called subscriber's talking connection.

2. In a telephone system, a talking connection including a two-wire junction line, two relays each connected to a different line branch of said junction at one end thereof, means directly associated with the other end of said junction for operating either of said relays, and means for complet- 125 130

ing a loop circuit through said relays over said junction.

3. In a telephone system, a talking connection extending between two exchanges connected by a two-wire junction line, two relays each connected to a different line branch of said junction at the outgoing end thereof, means associated with the junction at the distant exchange for operating either of said relays, and means for completing a loop circuit through said relays over said junction.

4. In a telephone system, a talking connection involving connecting means at a manual board, two relays each connected to a different line branch of the talking connection at the calling end thereof, means at the manual board for operating either of said relays and means for completing a loop circuit through said relays over the talking connection.

5. In a telephone system, a talking connection involving connecting means at a manual board, two relays each connected to a different line branch of the talking connection at the calling end thereof, means at the manual board for operating either of said relays, a loop circuit including said relays and the two line branches, manually operated means for opening said loop circuit, a disconnecting circuit controlled by said relays and means for disconnecting the talking circuit by opening the loop circuit.

6. In a telephone system, a talking connection involving connecting means at a manual board, two relays each connected to a different line branch of the talking connection at the calling end thereof, means at the manual board for controlling said relays and means controlled by said relays and operated from the manual board to transfer the control of the disconnection into the hands of the manual operator.

7. In a telephone system, a talking connection involving connecting means at a manual board, two relays each connected to a different line branch of the talking connection at the calling end thereof, means at the manual board for controlling said relays, means controlled by said relays and operated from the manual board to transfer the control of the disconnection into the

hands of the manual operator and means for operating said relays from the side of the calling subscriber so as to effect the disconnection of the talking circuit when not extended through a manual board.

8. In a telephone system, a talking connection involving connecting and supervisory means at a manual board, two relays each connected to a different line branch of the talking connection between the manual board and the called party, means for controlling said relays from the called end of the connection and supervisory circuits controlled by said relays.

9. In a telephone system, a talking connection involving connecting and supervisory means at a manual board, two relays each connected to a different line branch of the talking connection between the manual board and the called party, means for controlling said relays from the called end of the connection, means for operating a busy flash signal through said relays and means for operating a clearing signal through said relays.

10. In a telephone system a talking connection extending between two exchanges connected by a two-wire junction, manually operated means at the first exchange for extending the connection to the second exchange, automatic means for extending the connection in the second exchange, two relays each connected to a different line branch of said junction at the incoming end thereof, means for controlling said relays from the called end of the connection and supervisory signals at the first exchange controlled through said relays.

11. In a telephone system, a talking connection extending between two exchanges connected by a two-wire junction, two relays each connected to a different line branch of said junction at the outgoing end thereof, two other relays each connected to a different line branch of said junction at the incoming end thereof, means for operating either of the two relays last mentioned from the called end of the talking connection and means for operating either of the two relays first mentioned through the said other relays.

OSCAR GRAHN.
